(57) **CLAIM**

The ornamental design for a frying pan, as shown and described.

DESCRIPTION

FIG. 1 shows a top view of my design for a frying pan; FIG. 2 shows a first top, front and side perspective view thereof from a first angle; and, FIG. 3 shows a second top, front and side perspective view thereof from a second angle. The bottom and remaining side views, which are not shown, form no part of the claimed design.
